S. W. GOODALL

CARBURETOR

Filed Dec. 30, 1925

Inventor

S. W. Goodall
By Samuel Herrick,
Attorney

UNITED STATES PATENT OFFICE.

SAMUEL W. GOODALL, OF PHOENIX, ARIZONA.

CARBURETOR.

Application filed December 30, 1925. Serial No. 78,374.

This invention relates to carburetors and it has for its object to provide a simple and inexpensive device of this character which will be wholly free of moving parts, so that 5 there will be nothing to get out of order or adjustment.

The invention will be readily understood by reference to the accompanying drawing, wherein:

10 Fig. 1 is a side elevation showing the attachment of the carburetor to the intake manifold of an internal combustion engine,

Fig. 2 is a perspective view of the carburetor,

15 Fig. 3 is a horizontal sectional view therethrough,

Fig. 4 is a longitudinal sectional view, upon line 4—4 of Fig. 3, and

20 Fig. 5 is a transverse sectional view therethrough upon line 5—5 of Fig. 3.

Like numerals designate corresponding parts throughout the several figures of the drawing.

In the drawing, 5 designates the exhaust 25 manifold and 6 the intake manifold of an internal combustion engine. The carburetor 7 is connected with the intake manifold by a pipe 8, and with a source of gasoline supply by a pipe 9, and with a source of heated air by a pipe 10, the pipe 10 connecting with a stove 11, which surrounds the exhaust pipe of the engine. The carburetor proper comprises a box-like casing 12, having a cover 13, and a bottom 14. This casing is 30 divided internally by partitions 15 and 16, into chamber 17, 18 and 19. Pipe 8 leads from the chamber 17 and the chambers 17 and 19 are in communication with each 35 other through a port 20. The chambers 18 and 19 are in communication with each other through a port 21. The gasoline supply pipe 9 (see Fig. 3) conducts gasoline to the chamber 18, the gasoline passing from said chamber through port 21 to the chamber 40 19 and from the chamber 19 to the chamber 17 through the port 20. The pipe 8 leads from the chamber 17 at a point above the level of the gasoline therein. Heated air 45 through pipe 10 enters the carburetor at 22 (see Fig. 3). A plurality of spaced V-shaped partitions 24, 25, 26, 27 and 28, have ports 29, 30, 31, 32 and 33 formed therein, upon alternately opposite sides of the point

of entry 22 of pipe 10, so that the air is caused to travel through a tortuous passage-way, as indicated by the arrows, finally passing through port 33 into chamber 19, thence through port 20 to chamber 17 and out through pipe 8 to the intake manifold 55 6. The gasoline level in the carburetor is 60 such that a body of gasoline lies within the passages between the V-shaped partitions 24 to 28, this level being maintained at about the level of the ports; or in other words, the casing 12 is maintained about half full. 65 It is common practice to maintain the gasoline at a predetermined level in structures of this character. Floats are usually resort ed to for this purpose and I may accomplish the desired result in that way. 70 However, such float does not necessarily have to be located within the body 12 but might be located at any point in communication within the supply line 9. Thus, it will be seen that the pipe 8 leaves at a point above 75 the level of the gasoline so that only vapor will be drawn into said pipe. The air drawn in through pipe 10 bubbles up through the gasoline within partition 24 on its way to port 29. This bubbling of the 80 gasoline agitates, to some degree, the gasoline in the adjacent passages. Thus, the air is thoroughly carbureted or impregnated with gasoline vapors, said vapors being finally drawn off through pipe 8 to the intake manifold for use in the engine. While I have used the term gasoline in this specification, it is to be understood that any other suitable volatile liquid fuel is the equivalent 85 thereof. 90

It is to be understood that the invention is not limited to the precise construction set forth but that it includes within its purview whatever changes fairly come within either the terms or the spirit of the appended 95 claim.

Having described my invention, what I claim is:

A carburetor comprising a casing, a pair of partitions therein dividing said casing 100 into three chambers, said partitions being provided with ports therethrough through which communication is established between said chambers, an air inlet pipe leading into the bottom of said casing, at the side thereof 105 remote from one of said partitions, a plural-

ity of spaced V shaped partitions between the point of entry of the air inlet pipe and the last named partition, each of said V-shaped partitions having a port formed therethrough, the ports in the successive partitions being disposed on alternately opposite sides of the point of entry of said air

inlet pipe, and an outlet pipe for carbureted air which lies at a point materially above the level of the ports through said V shaped partitions. ¹⁰

In testimony whereof he affixes his signature.

SAMUEL W. GOODALL.
